(57) **CLAIM**

We claim the ornamental design for a hummingbird feeder component, as shown and described.

DESCRIPTION

FIG. 1 is a front, top perspective view of a hummingbird feeder component in accordance with a first embodiment of the present invention;

FIG. 2 is a front elevation view of the hummingbird feeder component of FIG. 1;

FIG. 3 is a rear elevation view of the hummingbird feeder component of FIG. 1;

FIG. 4 is a right elevation view of the hummingbird feeder component of FIG. 1;

FIG. 5 is a left elevation view of the hummingbird feeder component of FIG. 1;

FIG. 6 is a top plan view of the hummingbird feeder component of FIG. 1;

FIG. 7 is a bottom plan view of the hummingbird feeder component of FIG. 1;

FIG. 8 is a front, top perspective view of a hummingbird feeder component in accordance with a second embodiment of the present invention;

FIG. 9 is a front elevation view of the hummingbird feeder component of FIG. 8;

FIG. 10 is a rear elevation view of the hummingbird feeder component of FIG. 8;

FIG. 11 is a right elevation view of the hummingbird feeder component of FIG. 8;

FIG. 12 is a left elevation view of the hummingbird feeder component of FIG. 8;

FIG. 13 is a top plan view of the hummingbird feeder component of FIG. 8; and,

FIG. 14 is a bottom plan view of the hummingbird feeder component of FIG. 8.

Broken lines and unshaded portions entirely contained within broken line are not claimed. In FIGS. 1-5, 7-12 and 14 the broken lines in the form of an alternating series of relatively short dashes and relatively long dashes represent the bounds of the claimed design.
